OF DETROIT, MICHIGAN.

FLUSHING-TANK FOR WATER-CLOSETS.

1,247,211.

Specification of Letters Patent.

Patented Nov. 20, 1917.

Application filed March 30, 1917. Serial No. 158,490.

To all whom it may concern:

Be it known that I, ADDY A. Boss, a citizen of the United States, residing at Detroit, in the county of Wayne and State of Michigan, have invented a new and useful Flushing-Tank for Water-Closets, of which the following is a specification.

This invention relates to flushing tanks for water closets, and particularly to flushing tanks such as are intended to be located only a slight distance above the bowl to be flushed.

It is the object of the invention to subject the water discharging from a flushing tank to the pressure existing in the mains from which the tank is filled in addition to that resulting from the weight and elevation of the water so that a discharge of water sufficiently forceful to thoroughly cleanse a closet bowl may be secured without undesirably elevating the flushing tank or unduly increasing its capacity.

In attaining this object the invention contemplates the employment of a flushing tank the upper portion of which will normally be occupied by air under pressure of the water in the mains, and the utilization of this pressure to initially open the discharge valve of the tank after manipulation of a certain lever. Other features are the provision of automatic means for controlling the access of air to the tank, of means for holding the discharge valve raised after loss of the air pressure utilized to initially elevate said valve so as to allow the tank to fully discharge, and the provision of means for by-passing a certain amount of water past the discharge valve after the same has closed, so as to refill the trap of the closet and leave a supply of water standing in the bowl.

One embodiment of a construction accomplishing said object is hereinafter described and is illustrated in the accompanying drawings, wherein:

Figure 1 is a sectional elevation of a flushing tank employing said construction, said tank being shown in its normal or filled condition.

Fig. 2 is a top view of the same.

Referring now more particularly to the drawings wherein like reference characters designate similar parts in both the figures, 1 denotes an air-tight tank, preferably of sheet metal construction. Water inlet and

outlet pipes 2 and 3 respectively communicate with the tank 1 through the bottom thereof, the latter pipe being relatively large so that the tank will quickly empty when discharging, despite the simultaneous inflow of water through the pipe 2. The pipe 2 communicates with any suitable source of water pressure as the mains of a pumping system (not shown), and has open communication with the tank so that normally the latter will be almost filled with water under the pressure in the mains, the space above the water being occupied by air under the same pressure.

Within the tank, the pipe 3 is screwed into the lower end of a valve case 4 the top of which forms a seat for a disk valve 5 controlling the flow of water through said valve case to the outlet pipe. Said valve seat is lined with rubber, leather, or similar yielding material as indicated at 6 to prevent leakage, this lining being held in place by a clamping ring 7 bolted or otherwise secured to the top of the valve case. In its movement to and from its seat, the valve is guided by a pin 8 projecting rigidly downward therefrom and passing freely through a guide strip 9 which abridges the central passage through the valve case. The valve is provided also with an elongated upstanding lug 10, which is pivotally engaged with the lower extremity of a valve stem 11. The upper end portion of said valve stem projects above the tank passing centrally through an opening 12 formed in the top thereof and through a flexible diaphragm 13 which forms a closure for said opening. The outer portion of this diaphragm is engaged between the tank top and a clamping ring 14, the clamping pressure being set up by bolt and nut fastenings 15 between said ring and tank. The center portion of the diaphragm is engaged between washers 16 through which the stem 11 passes, which washers are clamped by nuts 17 threaded upon said stem. Thus it will be seen that the valve stem and consequently the valve are constrained to participate in any upward movement to which the center portion of the diaphragm may be subjected due to the compression of the air in the top portion of the tank under normal conditions. Such movement of the diaphragm is normally prevented, however, by a rock-shaft 18 horizontally mounted in bearings 19, up-

standing upon a strip 20. This strip is integral with and diametrical to an annular flange 21 formed upon the ring 14 at its inner periphery. The stem 11 passes freely 5 through this strip and is adapted in one position of rotation of the rock-shaft to abut against a flat surface 22 of said rock-shaft produced by cutting away a small portion thereof. By rocking this shaft through an 10 angle of approximately ninety degrees, the flat portion thereof will be displaced from above the valve stem and the latter, together with the valve, will then be raised through outward yielding of the diaphragm to the 15 air pressure therebeneath. At the front of the tank a handle member 23 is mounted fast upon the rock-shaft, whereby the latter may be conveniently rocked from one to the other of the described positions.

20 Since the initial unseating of the valve 5, after proper manipulation of the handle 23, is due to air pressure in the top portion of the tank acting on the diaphragm 13, and since this pressure is quickly reduced as the 25 water rapidly discharges from the tank, it is apparent that provision must be made to prevent the valve from seating again after the water level has been somewhat lowered. With this in view, a latch member 24 is provided to engage a shoulder 25 in the lug 10 when the valve is in raised or open position, said shoulder being formed by notching an edge of the lug. Said latch member is horizontally slidable upon a bracket 26 30 which has a guide portion 27 freely embracing said latch member. This bracket furthermore forms the pivotal support for a bell crank lever 28 having a normally vertical arm pivotally connected to the latch member, as indicated at 29, and having a normally horizontal arm, the free end of which carries a float 30. Normally, the float 30 is submerged and the buoyant force thereof acts through the bell crank lever 40 upon the latch member 24, tending to force the latter against the lug 10, consequently 45 upon initial raising of the valve by the air pressure exerted upon the diaphragm 13, the latch member will engage beneath the shoulder 25 and will thus retain the valve 50 opened until the tank has been almost completely emptied. When the water has reached this low level, however, the float 30 will have dropped to the position indicated 55 in dash lines in Fig. 1, thereby rocking the bell crank lever to the position similarly indicated and withdrawing the latch member from engagement with the lug 10. The valve 5 will now drop to its seat due to its own weight and that of the stem 11, and the tank will be filled again by the inflow 60 through the pipe 2.

While the bracket member 26 may be supported in any convenient manner, it is preferred to mount the same upon a vertical

water tube 31 which has its lower extremity screwed into a lateral projection 32 upon the valve case 4 and communicating through a passage 33 in said projection with the main passage through said case. The top 70 of the water tube 31 is screwed into the bottom of a T-fitting 34, the top of which forms a seat for a disk valve 35. Movement of this valve to and from its seat is guided by a pin 36 projecting rigidly downward from the valve and having sliding engagement with a guide strip 37 abridging the passage beneath the valve. A short stem 38 projects rigidly upwardly from the valve 35 and has its upper end pivotally engaged with one 80 extremity of an intermediately pivoted lever 39 which carries a float 40 at its other end. When the water in the tank is at its normal level, as illustrated, the buoyant force of the float 40 acts to maintain the valve 35 85 closed, as is shown in full lines in Fig. 1, but when the level falls a certain distance below normal, said float will drop to the position shown in dash lines in Fig. 1, and the valve 35 will be opened through the 90 lever 39, as likewise indicated in dash lines. The lateral opening 41 of the T-fitting 34 communicates with an air vent pipe 42, which, after extending to a point above the normal water level, projects through an end 95 wall of the tank and into communication with the external atmosphere.

In considering the operation of the above-described mechanism, it will be first assumed that the water level and the position of the 100 several mechanisms are all normal. The air occupying the top portion of the tank is then compressed by the water which fills the main portion of the tank, the degree of the pressure being equal to that existing in 105 the inlet pipe 2. Under these conditions, the buoyancy of the submerged float 40 will maintain the valve 35 closed and prevent water being forced out through the air vent pipe 42 by said pressure. It being desired 110 to discharge the contents of the tank, the handle 23 is manually rocked from its full line to its dash line position (see Fig. 1). The shaft 18 is thus rocked through substantially a ninety degree angle, displacing 115 its flat portion from above the valve stem. The tendency of the diaphragm to expand upwardly under pressure of air beneath the same will no longer be resisted by the valve stem 11, and the diaphragm will bulge up, 120 lifting said stem and unseating the valve 5. Thereupon, the buoyant force of the float 30 will throw the latch member 24 into engagement with the shoulder 25, so that the valve may not reseat as soon as the air pressure acting on the diaphragm is reduced. The water rushes out through the fitting 4 and pipe 3, and thence to the closet bowl (not shown). The pressure inducing this discharge is that of the air compressed above 125 130

the water as well as the hydrostatic pressure of the water itself. There is an inflow through the pipe 2 simultaneous with the outflow through 3, and this retards to some extent the lowering of the water level and the expansion of the air. When the water level has fallen sufficiently to cause the float 35 to move downwardly, the air pressure above the water will be practically atmospheric. If the tank were now vented, the further dropping of the water level would be impeded by the entrance of air through the discharge pipe. The lowering of the float 40, however, opens the valve 35 so that air flows into the tank through the pipe 42 as the water level drops. Finally, when the tank is almost empty, the float 30 drops sufficiently to disengage the latch member 24 from the lug 10, and the valve 5 regains its seat. At this time the handle 23 rocks downwardly by its own weight and engages the flat portion of the rock-shaft 18 above the stem 11. The tank now quickly fills with water entering through the pipe 2, and the floats 30 and 40 successively regain their normal elevated positions as the water level rises. But before the valve 35 is closed by the float 40, a sufficient quantity of water will be by-passed through the water tube 31 and passage 33 to fill the trap of the closet and the depression in the bottom of the bowl.

In addition to the utilization of the water main pressure to augment the force with which the water discharges, the above-described construction is advantageous in that the exertion of a very slight manual force is necessary to cause flushing, since the only weight raised by said exertion is that of the small handle 23.

What I claim is:

1. In a device of the character described, the combination with a substantially air-tight tank, having an outlet in its bottom portion, of means for admitting water under pressure to said tank and thereby compressing air in the top portion thereof, a valve controlling said outlet, means for employing the energy of the compressed air in the top of the tank for unseating said valve, a manually controlled device exterior to the tank for normally preventing the last-named means from functioning, means adapted to retain the valve open after its initial unseating independently of the degree of air pressure in the top of the tank, and float-controlled mechanism for releasing the valve from the last named means at a predetermined level of the water in the tank.

2. In a device of the character described, the combination with a substantially air-tight tank, having a water inlet and an outlet and provided with an opening in its top, of a diaphragm closing said opening

and subject to the pressure of air in said tank, a valve controlling said outlet, a connection between the valve and diaphragm whereby outward flexing of the latter unseats the former, a member exterior to the tank adjustable to either permit or prevent outward flexing of the diaphragm, means adapted to retain the valve open after its initial unseating independently of said diaphragm, and float controlled mechanism for releasing the valve from the last-named means, at a predetermined level of the water in the tank.

3. In a device of the character described, the combination with a substantially air-tight tank, having a water inlet and an outlet and provided with an opening in its top, of a diaphragm closing said opening and subject to the pressure of air in said tank, a valve controlling said outlet, a stem for said valve extending through said diaphragm and having an engagement therewith whereby outward flexing of the diaphragm unseats the valve, a member exterior to the tank movable into or out of an engagement with said stem, preventing upward displacement thereof and outward flexing of the diaphragm, means adapted to retain the valve open after its initial unseating independently of said diaphragm, and float controlled mechanism for releasing the valve from the last named means at a predetermined level of the water in the tank.

4. In a device of the character described, the combination with a substantially air-tight tank having an outlet in its bottom portion, of means for admitting water under pressure to said tank, and thereby compressing air in the top portion thereof, a valve controlling said outlet, a stem extending from said valve and projecting exterior to the tank, mechanism engaging said stem and operable for unseating the valve by the pressure of the air compressed in said tank, a rockshaft exterior to the tank normally engaging said stem to maintain the valve seated and manually disengageable therefrom, means independent of the air pressure in the tank for holding the valve open after initial unseating thereof, and float controlled mechanism for automatically releasing the valve from the last named means at a predetermined level of the water in the tank.

5. In a device of the character described, the combination with a substantially air-tight tank having an outlet in its bottom portion, of means for admitting water under pressure to said tank and thereby compressing air in the top portion thereof, a valve controlling said outlet, means operable by the pressure of the air in the top of the tank for unseating said valve, a manually controlled device exterior to the tank for

normally preventing the last named means from functioning, means adapted to retain the valve open after its initial unseating independently of the degree of air pressure in the top of the tank, float controlled mechanism for releasing the valve from the last named means at a predetermined level of the water in the tank, a pipe for venting the tank to the atmosphere, a valve controlling said vent pipe, and means for automatically actuating said valve controlled by variations in the water level.

6. In a device of the character described, the combination with a substantially air-tight tank, having an outlet in its bottom portion, of means for admitting water under pressure to said tank and thereby compressing air in the top portion thereof, a valve controlling said outlet, means for employing the energy of the compressed air in the top of the tank to unseat said valve, a manually controlled device exterior to the tank for normally preventing the last named means from functioning, means adapted to retain the valve open after its initial unseating independently of the degree of air pressure in the top of the tank, float controlled mechanism for releasing the valve from the last named means at a predetermined level of the water in the tank, and means for by-passing a limited quantity of water around said valve subsequent to discharging of the tank.

7. In a device of the character described, the combination with a substantially air-tight tank, having an outlet in its bottom portion, of means for admitting water under pressure to said tank and thereby compressing air in the top portion thereof, a valve controlling said outlet, means for employing the energy of the compressed air in the top of the tank for unseating said valve, a manually controlled device exterior to the tank for normally preventing the last named means from functioning, means adapted to retain the valve open after its initial unseating independently of the degree of air pressure in the top of the tank, float controlled mechanism for releasing the valve from the last named means at a predetermined level of the water in the tank, a by-pass around said valve, a valve controlling said by-pass, a float normally maintaining said valve closed and opening the same as the tank discharges, said float operating to open the valve as the tank fills subsequent to allowing a limited discharge of water through the by-pass.

8. In a device of the character described, the combination with a substantially air-tight tank having an outlet in its bottom

portion, of means for admitting water under pressure to said tank and thereby compressing air in the top portion thereof, a valve controlling said outlet, means for employing the energy of the compressed air in the top of the tank to unseat said valve, a manually controlled device exterior to the tank for normally preventing the last named means from functioning, means adapted to retain the valve open after its initial unseating independently of the degree of air pressure in the top of the tank, float controlled mechanism for releasing the valve from the last named means at a predetermined level of the water in the tank, a by-pass around said valve, a pipe for venting the tank to the atmosphere, a common valve controlling said by-pass and vent pipe, and a float controlling said valve to open the same and vent the tank as the water discharges, and closing the valve as the tank fills subsequent to allowing a limited discharge of water through said by-pass.

9. In a device of the character described, the combination with a substantially air-tight tank having an outlet in its bottom portion, of means for admitting water under pressure to said tank and thereby compressing air in the top portion thereof, a valve controlling said outlet, a stem for said valve having a portion projecting exteriorly of the tank, means engaged with said stem for employing the energy of the compressed air in the top of the tank to unseat said valve, a member exterior to the tank engageable with the stem to prevent the same undergoing a valve-opening displacement and adjustable to allow such a displacement, means adapted to retain the valve open after its initial unseating independently of the degree of air pressure in the top of the tank, and means for automatically releasing the valve from the last-named means at a predetermined level of the water in the tank.

10. In a device of the character described, the combination with a tank having an outlet, a valve for closing said outlet, means for seating and unseating said valve, a by-pass around said valve, a pipe for venting the tank to the atmosphere, a common valve controlling said by-pass and vent pipe, and a float controlling the last-named valve to unseat the same and vent the tank as the water discharges and to close the same as the tank fills subsequent to allowing a limited discharge through said by-pass.

In testimony whereof I sign this specification.

ADDY A. BOSS.
